UNITED STATES PATENT OFFICE.

WILLIAM R. LONSDALE, OF CLEVELAND, OHIO.

EXPANSION-JOINT CUSHION.

1,085,275.

Specification of Letters Patent.

Patented Jan. 27, 1914.

Application filed January 18, 1913. Serial No. 742,789.

To all whom it may concern:

Be it known that I, WILLIAM R. LONSDALE, a citizen of the United States, residing at Cleveland, in the county of Cuyahoga and

5 State of Ohio, have invented a certain new and useful Improvement in Expansion-Joint Cushions, of which the following is a full, clear, and exact description.

This invention relates to an expansion 10 joint cushion and has for its object the provision of a previously formed or completed expansion joint cushion as an article of manufacture, which can be inserted in any structure or construction which requires an 15 expansion joint, as the construction progresses and remains a permanent part thereof.

It is customary and, in fact, necessary to provide at intervals in various types of construction, such as pavements, walls, and the like formed from blocks, cement or concrete, expansion joints to allow for expansion and contraction of the structure due to temperature changes.

25 It is customary at the present time and in fact it is practically the universal custom to form the expansion joints by placing at intervals in the construction, temporary wooden strips between the blocks or sections 30 of the material of which the structure is

formed, and later to remove the wooden strips and fill the spaces previously occupied by them with a melted bituminous substance such as bitumen which when har-

35 dened or cooled is semi-solid or sufficiently pliable or yieldable to contract and expand in accordance with the movements of the structure. This method has numerous dis-

40 advantages among which may be mentioned that it is somewhat difficult to remove the strips, particularly between the blocks or sections of certain types of constructions; it is often the case that the edges of the blocks or sections are chipped in removing the

45 strips; it is necessary to maintain at the site of the work or construction apparatus for heating, melting and pouring the bituminous substance which is to be used as the expansion joints. It has also been proposed to

50 provide between the sections of a construction a metal trough-like container into which the melted bituminous substance can be poured. This method, however, has not proven to be very satisfactory, and is not used to any extent.

The device forming the subject matter of

my invention is, as previously stated, a complete expansion joint cushion which will be previously formed of the proper dimensions as to width and depth, and if desired, as to 60 length, although the cushion may be made of any length and later cut into the shorter lengths which the construction may require.

When my previously formed expansion joint cushion is employed in a construction 65 as the same progresses, there is effected a considerable saving of time and labor over that which must be expended with the present methods, and in very many instances, a more satisfactory joint can be provided by 70 placing permanently in position a previously formed expansion joint cushion than is possible with the present method of placing in the construction the temporary filler and spacer and then after the construction has 75 progressed beyond the same, to substitute for that filler and spacer a permanent expansion joint.

I shall now describe my improved expansion joint cushion in the form best known 80 to me, and the preferred manner of producing it, reference being had to the accompanying drawing wherein the single figure is a perspective view of a portion of the expansion joint cushion with parts broken 85 away for the sake of clearness.

The expansion joint cushion, when completed in the form best suited for use in pavements, is about an inch thick, about six inches wide, and as long as desired,—usually 90 8 or 10 feet. The completed cushion consists of a body portion 10^a made of suitable bituminous or equivalent material, such as asphaltum or pitch,—having a thin outer shell or covering 10^c made of fibrous, porous 95 material, such as paper or cloth; and an embedded trough-shaped member 10^b made of metal having many holes through it, such as wire mesh or expanded metal,—said metal member being disposed in substantial en- 100 gagement with the thin outer shell or covering.

The preferred manner of producing the said cushion is as follows: The paper or cloth for the outer shell is bent into trough 105 form and is placed in a mold of the desired shape and size so that the bottom and sides of said shell will engage with and be supported by the mold walls. Then the trough shaped metal member is put inside the paper 110 or cloth trough, so that by engaging the same it will hold it against the walls of the

5 mold, particularly when the melted bituminous material is poured in. While the paper or cloth cover and the metal member are in the mold, as stated, the melted bituminous material is poured into the paper or cloth trough and allowed to solidify. The material, of course, will pass through the interstices of the metal member so as to entirely embed the same.

10 10 The complete expansion joint cushion, removed from the mold may be handled and transported conveniently. In cold weather when the bituminous material becomes more or less brittle, the embedded metal member will add sufficient strength to the cushion to prevent any considerable breakage. In warm weather when the bituminous material is soft and sticky, the outer covering or shell makes the handling of the cushion possible without getting bituminous material smeared upon the hands. The said expansion joint cushion may be laid in the pavement in any kind of weather. It does not perform the function for which it is provided except in warm weather, because in cold weather there is no expansion of the pavement in which it is laid. When, however, the weather gets warm and the pavement does expand, the pressure applied to the included expansion joint cushion will be such as will force the bituminous material through the thin porous shell or cover 10°, so that it will become adherent to the adjacent pavement. There will be no spaces left, either when the pavement is laid, or at any other time between the cushion and the pavement.

15 20 25 30 35 40 45 50 55 60 65

As stated in the introduction, this cushion

is adapted for use in pavements or in any structure made of cement, concrete, or blocks, where expansion joints are required. It is made in long lengths and may be cut to any required length. When used in pavements, it is intended to be used as a complete substitute for the filled joints now common. The described cushion strips may be placed between the curb and the pavement for the entire length of the street. At intervals continuous strips extending across the street are interposed between sections of the pavement, whether the pavement be made of blocks, bricks, concrete or anything else.

Having described my invention, I claim:

1. An expansion joint cushion for pavements and the like comprising a thin flat elongated body of bituminous material having an adhering thin porous covering of fibrous material and having an embedded trough-shaped foraminous metal member extending from one end to the other of said body.
2. An expansion joint cushion for pavements and the like comprising an elongated body of bituminous material having an adhering thin porous outer covering of fibrous material and having an embedded trough-shaped foraminous metal member in substantial contact with said outer covering.

In testimony whereof, I hereunto affix my signature in the presence of two witnesses.

WILLIAM R. LONSDALE.
